Primary Examiner — Selina Sikder(74) *Attorney, Agent, or Firm* — Bacon & Thomas, PLLC(57) **CLAIM**

The ornamental design for a push button switch with a display device, as shown and described.

DESCRIPTION

FIG. 1 is a front view of a push button switch with a display device showing my new design;

FIG. 2 is a rear view of the push button switch with a display device shown in FIG. 1;

FIG. 3 is a left side view of the push button switch with a display device shown in FIG. 1;

FIG. 4 is a right side view of the push button switch with a display device shown in FIG. 1;

FIG. 5 is a top view of the push button switch with a display device shown in FIG. 1;

FIG. 6 is bottom view of the push button switch with a display device shown in FIG. 1; and,

FIG. 7 is front perspective view of the push button switch with a display device shown in FIG. 1.
